GRILL MOUNTABLE BASTING SAUCE PAN

James A. Rader, Lamar, Mo., assignor to New World
Bar-B-Q Accessories, Inc., Lamar, Mo.

Filed Jan. 30, 1975, Ser. No. 545,607

Term of patent 14 years

Int. Cl. D7—99

U.S. Cl. D7—37

Fig. 1

Fig. 2

Fig. 3

Fig. 4

FIG. 1 is a perspective view of a grill mountable basting sauce pan showing my new design;

FIG. 2 is a top plan view;

FIG. 3 is a side elevational view; and

FIG. 4 is an end view as seen from the right of FIG. 3.

I claim:

The ornamental design for a grill mountable basting sauce pan, as shown.
